UNITED STATES PATENT OFFICE

JOSEPH T. COCHRAN, OF CHICAGO, ILLINOIS

SIGN CHARACTER

Application filed July 14, 1930. Serial No. 467,855.

This invention relates to sign letters or characters made of glass or other transparent material and having a rear reflector, and to the method of producing such characters.

5 One of the principal objects of the invention is in the provision of a sign letter or character composed of transparent material either plain or colored and adapted to resemble the present electrical gas filled tube, 10 when it is illuminated.

A further object of the invention is in the provision of a reflecting character which is simple and inexpensive, not likely to break and easily applicable for display purposes 15 whether illuminated or not.

A further object of the invention is in the provision of a character having a reflecting surface made up of a great number of relatively small projections or indentations 20 which together form a reflecting surface visible through a side angle from the front thereof.

A still further object of the invention is in the provision of a character of this kind in 25 which a great number of reflecting surfaces are magnified by a lens portion and visible through a side angle from the front of the character.

Other objects of the invention are in the 30 method of producing a letter or character from transparent plastic material; in the method of removing surplus plastic material of the formation of the character; in the method of preparing and applying a reflector 35 from a sheet of reflecting material; in the method of curving a reflector to apply to the back of a letter or character; and in general in providing the new and improved method of making sign letters and characters as herein 40 shown and described.

The accompanying drawing illustrates more or less diagrammatically an embodiment of the invention and the method of producing letters or characters of this kind. 45

In the accompanying drawing:

Fig. 1 is a sectional view of a mold as taken on the line 1—1 of Fig. 5 with a scraper or roller in elevation above it;

50 Fig. 2 illustrates a sheet of reflecting ma-

terial from which reflecting characters are cut;

Fig. 3 is an elevation of the rollers for shaping the characters cut from the reflector;

Fig. 4 is a section of a letter or character showing a tie for holding the reflector and character body together;

Fig. 5 is a face or plan view of a mold as shown in Fig. 1 for form letters or characters; and

Fig. 6 represents a character constructed in accordance with this invention and receiving light from two sources for illuminating it.

One of the difficulties in forming letters 65 or characters of transparent plastic hardening material such as glass is in the provision of a suitable reflecting surface which is visible at different angles or in a wide angle from the front of the character. In the 70 present invention it is proposed to overcome this objection by making a transparent body with a flat or plain back and to apply thereto a curved reflecting surface of innumerable small reflectors which together provide a 75 reflecting surface visible from a wide angle at the front of the character and magnified by the lens thereof.

Referring now more particularly to the drawing, a letter or character of the desired 80 shape, size or configuration is formed of glass or other suitable hardening plastic material by pouring a quantity of the material in a plastic state in the formed recesses 9 of a mold 10. In the present invention the upper 85 edges 11 of the recesses forming the character are located in the same plane which is preferably the plane of the upper edges 12 of the sides of the mold and these edges 11 are preferably sharp so that when a scraper 90 or a roller 13 is moved over the top of the mold it will smooth the upper surface of the material, leveling it off and forming a plain back for the character, the surplus material dropping into depressions 14 in the mold from which they may be removed later. This 95 operation forms a character of the desired shape and size having a body portion 15 with a curved front surface 16 and a straight or plain back surface 17. The body of the char- 100

acter may be plain or colored and the outer curved surface forms a lens for magnifying and reflecting light rays from the back thereof.

5. In order to provide a reflector which is visible from a wide angle at the front of the character, the reflector is made from a thin sheet 18 of reflecting material in which there are innumerable facets or depressions 19 ar-

10 ranged in regular rows preferably staggered in relation to each other and the rows preferably extending transversely in relatively vertical and horizontal directions. The depressions 19 are represented in the present case by small circles but it will be understood that diamond, hexagonal and other angular facets may also be used in the same manner.

15 A reflector 20 similar in shape to the character body 15 is cut from the reflector sheet 18 and the portions making up the reflector are flat or are made slightly wider than the corresponding portions of the character body so that when curved as shown in Fig. 4 they will be of the same width as the portions of the body to which they are applied. The reflector portions may be curved in any suitable manner as for example by shaping them between a pair of complementary forming 20 rolls 21 and 22 as shown in Fig. 3 which makes them of the shape desired. After the character body and reflector are formed in the manner desired they are assembled and may be attached in corresponding position so that the reflector curves outwardly from the body of the character at the rear thereof, as by means of a fine cord or wire 23 which is practically invisible from the front of the character and by which the character itself 25 may be attached to a suitable support or fastened in position.

30 In utilizing signs of this kind the letters or characters are set up in a show window, on a sign board or elsewhere at some distance 45 from a beholder and one or more illuminating lamps 25 are arranged at suitable angles so that the rays therefrom will be reflected and diverted by the reflector 20 in a wide angle at the front of the sign. By placing the lamps at the sides, or at the top and bottom of the sign, a full play of the light rays 50 will be afforded so that a person passing the sign will receive the impression of a continuous glowing character, no matter what the 55 angle of vision may be. It will thus appear luminous and flaming and may be colored in a variety of colors which will give the general appearance of an electrified gas filled tube without the greater expense and danger 60 of breaking of the latter.

I claim:

1. A sign letter or character comprising a body with a front lens portion and a flat back, and a curved reflector at the back having an outline similar to and running with

the body of the letter or character and curved transversely of the body.

2. A sign character having a transparent body with a front lens portion and a flat back, and a curved reflector of an outline similar to the body spaced from the back thereof and extending continuously with the transparent body and curved transversely of the body.

3. A sign letter or character comprising a body of transparent material, a curved reflector at the back thereof, the reflector being of an outline similar to the body of the letter or character and formed with innumerable regular depressions for reflecting light rays in all directions and the edges of the reflector touching the edge portions of the letter or character.

4. A sign letter or character comprising a body of transparent material having a front lens portion and a flat back, a reflector of outline similar to and running with the letter or character and curved transversely to fit against the back of the letter and touching it only at the edges, and means for holding the reflector in contact with the letter or character.

5. A sign letter or character adapted to be illuminated from the front from one or more positions, comprising a transparent body portion having a front curved lens forming portion and a flat back, a reflector comprising a sheet of reflecting material having innumerable reflecting depressions arranged in regular staggered relation and of an outline similar to the character body, the reflector being curved transversely and having the edges only thereof in engagement with the rear edges of the corresponding parts of the body portion, and means for attaching the transparent portions and the reflector together.

6. A sign letter or character comprising a body with a front lens portion and a flat back, and a curved reflector at the back having an outline similar to and running with the body of the letter or character and curved transversely of the body, the reflector being formed with innumerable regular depressions for reflecting light rays in all directions.

JOSEPH T. COCHRAN.
